Primary Examiner — Terry Wallace

(74) Attorney, Agent, or Firm — Haynes and Boone, LLP

(57) **CLAIM**

The ornamental design for a culinary utensil, as shown and described.

DESCRIPTION

FIG. 1 is a front perspective view of a culinary utensil showing our new design.

FIG. 2 is a front view thereof.

FIG. 3 is a rear view thereof.

FIG. 4 is a right side view thereof, the left side being a mirror image.

FIG. 5 is a top plan view thereof; and,

FIG. 6 is a bottom plan view thereof.

The broken lines depict unclaimed subject matter and form no part of the claimed design.
